UNITED STATES PATENT OFFICE.

ARCHIBALD D. ADAMS AND FRED. L. ADAMS, OF PROPHETSTOWN, ILLINOIS.

BOLT.

SPECIFICATION forming part of Letters Patent No. 460,191, dated September 29, 1891.

Application filed February 7, 1891. Serial No. 380,585. (No model.)

To all whom it may concern:

Be it known that we, ARCHIBALD D. ADAMS and FRED. L. ADAMS, citizens of the United States, residing at Prophetstown, in the county 5 of Whiteside and State of Illinois, have invented a new and useful Door-Lock, of which the following is a specification.

This invention relates to door-locks, and has for its objects the improvement of the 10 same in the matters of durability, cheapness, and security.

With these objects in view the invention resides in the various novel details of construction and in the combination of parts 15 hereinafter fully described, and particularly pointed out in the claims.

In the drawings, in which we have illustrated our invention and in which like letters of reference indicate corresponding parts, Figure 1 shows a perspective view of a stable-door provided with our improved lock. Fig. 2 is a side elevation of the lock, the front plate having been removed. Fig. 3 is a detail perspective view of the keeper-plate, and Fig. 4 25 is a view, partly in section, of a door.

In the drawings, the letter A designates a casing or door-opening, to one side of which is hinged the door B. To the casing on the side opposite to which the door B is hinged 30 are fastened the hasps a a, which extend out from said casing a distance equal to the thickness of the door, or rather a distance equal to that level within or without the door upon which the bolts of the lock work.

35 C indicates the lock, and D the keeper-plates, which are necessary adjuncts to the lock on account of its peculiar construction. The lock C is provided with a case E.

F F' designate the lock-bolts, which extend 40 from the case E to the keeper-plates D. The bolt F is provided with a shoulder f near one end and with a loose collar f' between that end and the case E. Between the collar f' and the shoulder f there is a coiled spring 45 surrounding the bolt, which tends normally to press the bolt outward. Both bolts F F' extend within the casing and are attached therein to frames f² f³. These frames f² and f³ are counterparts of each other in every 50 particular. They are both in shape rectangular parallelograms and are both toothed upon one side interiorly, for a purpose to be

pointed out. Each one of these frames is provided with a lug f⁴, to which the bolts are attached, the only difference in the two cases 55 being that the lug f⁴ upon the frame, which is connected to the upper bolt, is upon the same side with the teeth, whereas the lug, which is connected to the frame to which the lower bolt is joined, is upon the side of the 60 frame opposite to that which is toothed.

G indicates a small cog-wheel, which is fast upon a shaft g, journaled in the case E and having upon its outer end a knob g'. The cog-wheel G fits within the two frames f² and 65 f³, intermeshing with the toothed sides of both.

In putting the lock together the frames f² and f³ are placed in such position as they will hold when the bolts F and F' are thrust outward to their greatest extent. The cog-wheel G is then placed within the frames f² and f³, and by such position its teeth will be intermeshed with the toothed sides of these frames. The collar f' will rest against the outside of 75 the case E, and upon the turning of the knob g' the frames will be retracted toward each other, thereby drawing in the bolts F F', and in so doing cramp the spring between the shoulder f and the collar f'. It will be evident that as 80 soon as the pressure upon the knob is released the spring will push the bolt F away from the case, and in so doing will cause the frame f² to resume the position originally occupied. As the frame f² moves to its normal position 85 under impulse from the coiled spring, as above described, it will cause the cog-wheel G to revolve, and as this meshes not only with the frame f², but also with the frame f³, and the teeth in these frames being arranged on 90 opposite sides, the revolution of the said cog-wheel will cause the frame f³ to resume its normal position and in so doing to thrust the bolt F' outward from the case.

The keeper-plates D D' are located over the 95 perforations b, which are provided in the door B for the purpose of enabling the hasps a a to extend through said door. The keeper-plate D is provided with a slot d, with a guide-loop d', within which the bolt F' is allowed 100 reciprocating motion. The keeper-plate D' is provided with a slot d, similar to that in the keeper-plate D and for a similar purpose—that is, for the purpose of receiving the hasp

2
 a—and also with a guide-loop d' , similar and for a similar purpose to the guide-loop d' on the keeper-plate D. The keeper-plate D' is provided with a spring-pressed pivoted catch d^2 , which is normally held above the slot d and in line with the opening in the guide-loop d' . By this construction when the bolt F has been withdrawn to its full extent from the hasp a and the door opened the spring-pressed catch d^2 will cover the slot d and be in line with the opening of the guide-loop d' , so that when the pressure upon the knob has been released and the spring-actuated bolt F tends to thrust forward the said spring-actuated bolt F will be restrained from motion by its end resting against the side of the catch d^2 . It will also be evident that upon the mere act of closing the door the bolts will thrust forward, as the said act of closing the door will cause the hasps a to project through the openings b and through the slots d, and in so doing to lift the catch d^2 , thus releasing the bolts and locking the door.

From the foregoing description it will be quite evident that this invention is a great improvement in door-locks, and especially in cases where a strong automatic lock is not only desirable but necessary.

We have illustrated the invention as applied to a stable-door, and its efficacy in this position will be apparent; but it may be applied in various other places with advantage.

Having thus described our invention, what we claim, and desire to secure by Letters Patent, is—

1. In a door-locking mechanism, the com-

bination, with the oppositely-acting bolts F F', the bolt F being provided with a shoulder f and a loose collar f' and a spring coiled upon the bolt between said shoulder and collar, 40 of casing E, the rectangular frames $f^2 f^3$, arranged within the casing in such manner that they are allowed a slight reciprocating motion upon each other, the said frames $f^2 f^3$ having their inner sides toothed, and a cog-wheel G, fast upon a shaft g, provided with a knob g' and meshing with the teeth of the frames, substantially as and for the purpose set forth.

2. In a door-locking mechanism, the combination, with the oppositely-acting bolts F F', one of which is spring-actuated, of the casing E, the rectangular frames $f^2 f^3$, arranged within the casing in such manner that they are allowed a slight reciprocating motion upon each other, the said frames $f^2 f^3$ having their inner sides toothed, a cog-wheel G, fast upon a shaft g, provided with a knob g' and meshing with the teeth of the frames, the staples a, the keeper-plates D D', and a spring-pressed pivoted catch d^2 in line with the bolt F, substantially as and for the purpose set forth.

In testimony that we claim the foregoing as our own we have hereto affixed our signatures in presence of two witnesses.

ARCHIBALD D. ADAMS.
FRED. L. ADAMS.
